BY *John Heidelberger*

ATTORNEY.

UNITED STATES PATENT OFFICE.

DAVID HEIDELBERGER, OF NEW YORK, N. Y.

CAP OR BONNET.

SPECIFICATION forming part of Letters Patent No. 430,473, dated June 17, 1890.

Application filed January 6, 1890. Serial No. 335,958. (No specimens.)

To all whom it may concern:

Be it known that I, DAVID HEIDELBERGER, a citizen of the United States, residing in the city, county, and State of New York, have invented a new and useful Improvement in Caps, Bonnets, &c., which improvement is fully set forth in the following specification and accompanying drawings.

My invention relates to a cap or bonnet made up of separable portions, the construction being hereinafter fully described, and definitely pointed out in the claims.

Figure 1 represents a perspective view of a cap embodying my invention. Fig. 2 represents a perspective view thereof, certain parts being separated and removed.

Similar letters of reference indicate corresponding parts in the two figures.

Referring to the drawings, A designates a child's cap formed of the parts B and C, the parts B composing the sides thereof, and the part C the top and back of the same. In the adjacent edges of said parts are openings or eyelets D, through which are passed the cords

or lacings E, whereby the parts are connected.

It will be seen that the cords E may be removed and withdrawn, whereby the parts

may be disconnected and separated—a feature of importance when the cap is to be washed or cleansed, or either part required to be repaired or replaced by a fresh piece of material. The frill F is connected with the adjacent portion of the cap by means of a cord or lacing G, which is passed through openings in the frill and cap, said frill, as is evident, being readily removable from the cap by withdrawing the cords.

The parts of the cap may be restored to their proper position and reconnected by reaving or passing the cords or lacings through the openings or eyelets, and tying or otherwise securing the ends of the same.

Having thus described my invention, what I claim as new, and desire to secure by Letters Patent, is—

A cap or bonnet made up of detachable sections united by a removable fastening and a frill detachably secured to said sections by a removable fastening, substantially as described.

DAVID HEIDELBERGER.
